UNITED STATES PATENT OFFICE

EDWARD E. CLEMENT, OF WASHINGTON, DISTRICT OF COLUMBIA.

TELEPHONIC APPARATUS AND SYSTEM.

1,109,622.

Specification of Letters Patent.

Patented Sept. 1, 1914.

Original application filed July 15, 1907, Serial No. 383,875. Divided and this application filed November 13, 1907, Serial No. 402,029. Renewed July 20, 1914. Serial No. 852,088.

To all whom it may concern:

Be it known that I, EDWARD E. CLEMENT, a citizen of the United States, residing at Washington, in the District of Columbia, have invented certain new and useful Improvements in Telephonic Apparatus and Systems, of which the following is a specification, reference being had therein to the accompanying drawing.

10 My invention relates to telephonic apparatus and systems, and has for its object the production of an improved and highly efficient impulse transmitter which may be used in systems employing automatic switches for 15 the purpose of interconnecting lines.

The machine I shall describe is applicable to many classes of systems, not all of which can be described herein, but some of which are disclosed in my prior applications, 20 among others as follows: Serial Numbers 309,010, March 20, 1906, (file 847); 323,096, June 23, 1906, (file 849); 328,723, August 1, 1906, (file 852); 323,096, June 23, 1906; 326,251, July 14, 1906, (file 858); 383,875, 25 July 15, 1907, (file 1137).

While the subject matter hereof is disclosed in several of the foregoing applications, especially in Serial No. 326,251, the present case is specifically a division of the 30 last named application Serial No. 383,875.

In the systems referred to, subscribers' lines are interconnected by means of automatic switches actuated by electromagnetic step-by-step mechanisms. Impulses of current are supplied to the electromagnets 35 through the switching circuits as determined by operators at the central office through the agency of push buttons or keys arranged after the fashion of the buttons on an adding 40 machine or the keys on a typewriter. Leading to each set of keys are ten wires, upon which for each cycle are imposed successively diminishing numbers of impulses from ten down to one. By connecting any one of 45 these wires to the switching circuits through the corresponding key, the number of impulses normal to that wire may be conveyed to the switches. These ten wires are supplied with their impulses from one or more

sending machines of the type presented 50 herein.

Briefly stated, the present invention comprises a drum mounted to rotate in suitable bearings, a commutator or circuit breaker on said drum which produces a constant succession of impulses; a set of overlapping contact springs with plugs or pitmen beneath them extending into proximity to the surface of the drum; and a series of cams on the drum for working these plugs and their associated contact springs. The arrangement of the commutator springs producing the unbroken series of impulses, and the other springs, which merely apply impulses to their respective wires, is such that the controlling springs make and break their contacts at points of zero potential on the main commutator bus wire, or in other words they break the circuit when the commutator springs are already open. By this means I 70 avoid sparking at any terminals other than those on the commutator which may be made very heavy and if necessary of material to resist the effects of sparking, such as carbon.

My invention is illustrated in the accompanying drawings in which—

Figure 1 is a side view of the drum and its connected parts. Fig. 2 is an end view thereof. Fig. 3 is an opposite end view, showing the driving motor and worm gear. Fig. 4 is a diagram on a reduced scale showing the surface of the drum, developed in a plane. Fig. 5 is a diagram showing the circuits of the machine.

Referring to the drawings, 1 and 2 indicate standards in which is rotatably mounted a shaft 3. To this is fixed a worm wheel 27 which engages with a worm 5 rotatably mounted upon the standard 2. Also secured upon the shaft 3 is a drum 6, the surface of which carries cam projections adapted to operate contacts mounted adjacent to the surface.

In the present instance the contacts operated by the drum are mounted upon a 95 bar or plate 7 which extends longitudinally over the surface of the drum and is supported by arms 8 and 9 which extend from

the supports 1 and 2. Each of the pairs of contacts (see Fig. 2 particularly) comprises two contacts 10 and 11 which are located one above the other and are so mounted as 5 to be insulated from each other. The contact 10 is maintained in elevated position by means of a stud 12 which rests upon the plate 7 and, passing through the lower contact 11, abuts against the lower side of the 10 contact 10. The lower contact 11 tends to occupy its lowest position, but may be moved upwardly into engagement with the contact 10 by means of an insulating stud or plug 13 which abuts against the lower side of the 15 contact 11, and, passing through the plate 7, has its lower end in position to be engaged by the drum so that when an elevated portion thereof is encountered, the plug will be raised and the contact 11 thrown against the 20 contact 10; while conversely a less elevated portion of the drum will permit the plug to fall and the contacts 10 and 11 to separate. At the extreme left-hand of the drum (see Fig. 1) are arranged equally spaced elevations 25 14 so that as the drum turns the pair of contacts 10 and 11 will be moved into and out of contact at equally recurring intervals. At the other end of the drum it will be seen that there are substantially triangular 30 shaped elevations 15, the angular edges of which are saw-toothed so that the successive sections of the drum upon which the plugs of the contact pairs *a*, *b*, *c*, etc., bear as the drum turns, are all of progressively increasing length so that the plug of the contact pair *a* will be elevated and therefore its contacts closed for a certain interval, the plug of the pair *b* will be elevated for a 35 greater interval, the plug of the pair *c* will be elevated for a still greater interval, and so on to the plug of the pair *j* which is held elevated for the longest interval. Those elevations on the drum section over which the plug corresponding to the contacts *a* passes, 40 are of such length that the plug will be maintained elevated and its contacts closed, while the contacts 10-11 of the commutator are made once. Similarly the pair *b* will be held closed while the contacts 10-11 are 45 made twice and so on to the pair *j*, the plug of which is held elevated while the contacts 10-11 are made ten times. In order to avoid the breaking of current upon other contacts than the pair 10-11, it is preferred 50 to make the elevations operating the contacts *a* to *j* of such lengths that their respective plugs will pass off those elevations after the plug corresponding to the contacts 10-11 has passed off an elevation. As 55 already stated in the preamble this avoids arcing at other contacts than the pair 10-11 and does away with the necessity for renewal of any other contacts except under extraordinary circumstances. The reason 60

for this will be clear upon reference to Fig. 65 5, wherein are shown circuits of the sending machine itself and also of a key set co-operating therewith. The general arrangement is such that individual wires 32 pass from the several pairs of springs *a*, *b*, *c*, *d*, 70 *e*, *f*, *g*, *h*, *i*, *j*, and are multiplied to the corresponding individual operators' keys OK, OK', OK², etc. The springs *k*, *l*, *m*, *n*, *o* and *s* are controlling springs, the first five controlling the relays R¹² to R¹⁷ inclusive, 75 which determine the connection of the successive strips of keys OK, OK', etc., for sending purposes. The spring sets *q*, *r*, control certain circuits which have no direct connection with the key set but affect certain other parts of the system. The commutator teeth 14 open and close the springs 10-11 so as to produce impulses in the wire 31, and so through the respective pairs of springs *a*, *b*, *c*, etc., to whichever button may 80 be down, and thence by the common wires 170, 176, etc., through the respective relay contacts 94, 95, etc., to the common wire 83, which passes to the apparatus which the impulses are intended to actuate. Since the 85 springs *a*, *b*, *c*, *d*, etc., are held closed continuously, each for a period sufficient to allow a number of impulses to pass, and since the individual impulses are all produced by the springs 10-11, which are 90 always apart at the instant when any of the springs *a*, *b*, *c*, etc., separate, it follows that there is no sparking except at the contacts 10-11, which can be made heavy enough and of the proper material to withstand the effects of such sparking. 95

Arranged alongside of the elevations 15 are other elevations 16 which are circumferentially co-extensive with their respective elevations 15 and are displaced longitudinally upon the drum so as to be in echelon thereon, and so that during the passage of an elevation 15 under the contact plugs, the corresponding elevation 16 will be passing under one of the plugs of the pairs of contacts *k* to *o*. Thus during the passage of the elevation 15 shown at the top of the drawing in Fig. 1, the corresponding elevation 16 will maintain the plug of the contact pair *k* elevated and those contacts closed. 110 During the passage of the next elevation 15 the corresponding elevation 16 will hold the plug of the contact pair *l* uplifted and those contacts closed. Similarly other elevations of the same nature will maintain their contacts closed during the passage of their corresponding elevations 15. These elevations 16 correspond to the respective sets of push buttons employed in the systems aforesaid and which may be employed in any system 115 in which impulses are to be transmitted in varying numbers. Other elevations 17 and 18 are provided upon the surface of the 120 125

drum, for the purpose of working spring arms *p*, *q*, *r* and *s* as the occasion may require. The particular arrangement of these cam surfaces may of course be varied to 5 meet the requirements of the particular circuit or system for which it is intended. The cams shown in the drawings herewith are those especially adapted to the telephone systems referred to.

10 In constructing the drum presented herein, I preferably make it of two castings 21 and 22 of brass or other suitable metal divided along a central peripheral line 20 (see Fig. 1). These castings are fitted at 15 their meeting edges in any suitable manner as by means of a rabbet joint or the like, and they are firmly secured together by bolts 23 extending from end to end of the frame.

In order to drive this machine, I may employ any suitable motor, but for purposes 20 of illustration I have shown an electric motor 24 secured by suitable couplings 25 to the worm shaft 26 whose worm threads intermesh with the main gear 27 mounted 25 on the central shaft 3. In the telephone systems referred to I have found that 12 revolutions per minute is the right speed and the worm and gear have therefore been cut so as to reduce the speed of the motor 24 from 30 approximately 1800 revolutions per minute to 12; but of course this reduction depends on the motor and can be made anything desired.

Fig. 3 not only shows the motor but also 35 shows the cam projections 15 in side elevation. There is one of these shorter than the others, shown as just beginning to pass under the plug of the contact pair *j*. This short cam is intended to give only four impulses instead of ten and is especially designed for selective ringing purposes in the telephone systems aforesaid.

I am aware that sundry changes may be made in the details of the machine here 40 presented and I do not therefore wish to confine myself to the actual specific details here described. For example, the cams may be made so as to give any desired number of impulses in a group, and there may be 45 only one cam effect or group of impulses per cycle or rotation, etc. My claims are therefore to be broadly construed.

Having thus described my invention, what 50 I claim and desire to secure by Letters Patent of the United States is:

1. In a telephone exchange system, automatic switches, and means for producing impulses to work the switches, in combination with a controlling or sending machine there- 55 for comprising the following instrumentalities: a supporting frame fitted with suitable bearings, a drum having a shaft mounted to turn in said bearings, a motor connected to said drum, a plurality of contact springs

overlying the drum, and cams of different 60 lengths on the surface of the drum adapted to work said springs to make and break their contacts during correspondingly different periods of time, whereby different numbers of impulses will be transmitted.

2. An impulse transmitter or sending machine comprising a frame with bearings, a selective cam drum or wheel mounted to turn in said bearings, a commutator having a continuous set of teeth and associated with said 70 cam drum, a contact overlying said commutator, a plurality of other springs overlying the cams on the drum, and operating studs for said springs, transmitting motion from the cams to the springs when the drum is 75 rotating, said cam actuated springs being connected on one side by a common conductor to the commutator contact and on the other side to diverse circuits and serving to distribute the impulses from the commutator 80 contact into said circuits.

3. An impulse transmitter or sending machine comprising a frame with bearings, a cam drum or wheel mounted to turn in said 85 bearings, a commutator having a continuous set of teeth and associated with said cam drum, a pair of springs overlying said commutator with an operating stud transmitting motion therebetween, a plurality of other 90 springs overlying cams on the drum, and operating studs for said springs, transmitting motion from the cams to the springs when the drum is rotated, said cam springs being connected to diverse circuits and serving to distribute the impulses from the commutator 95 springs into said circuits, and the cams on the drum being so proportioned with respect to the teeth on the commutator as to make and break when there is zero potential on the commutator springs, that is 100 to say when the latter are opened, so that 105 all sparking will be confined to said commutator springs.

4. An impulse transmitter or sending machine comprising an impulse generating device, and an impulse distributing device comprising distributing make and break contacts, in series with said impulse generating device, and means for selectively operating 110 said contacts to send impulses over a given circuit, said last named operating means being timed with respect to the impulse generating device to operate said distributing contacts at break periods between said impulses.

5. In combination, an impulse commutator, and an impulse selector and transmitter, the former producing a continuous series of impulses and the latter connected thereto so as to select and transmit any desired number of impulses at will, together with means for producing breaks in the transmitted impulses 115 at periods of zero potential on the com- 120

mutator, between the periods of impulse production thereof, whereby sparking at the transmitter contacts is prevented, substantially as described.

- 5 6. In combination, a continuous impulse producer, and an impulse selector and transmitter comprising one element connected to the impulse producer, and a plurality of co-operating elements connected to transmission circuits, with means to determine the

activity of one or more of said elements at will and the simultaneous inactivity of the other or others.

In testimony whereof I affix my signature in presence of two witnesses.

EDWARD E. CLEMENT.
